CARBIDE FEED MECHANISM FOR ACETYLENE GENERATORS

Filed April 7, 1948

FIG. 1

UNITED STATES PATENT OFFICE

2,480,292

CARBIDE FEED MECHANISM FOR
ACETYLENE GENERATORSHarry Hooper, New York, N. Y., assignor to Air
Reduction Company, Incorporated, a corpora-
tion of New York

Application April 7, 1948, Serial No. 19,453

11 Claims. (Cl. 48—53.3)

1

This invention relates to acetylene generators of the carbide to water type, and more particularly to the carbide feed mechanism of such generators.

It has been difficult heretofore to operate a bank of acetylene generators efficiently when the generators are connected to a common discharge line. Usually one or two of the generators operate at a higher pressure and carry the entire load instead of each generator contributing its proportionate quantity of the total gas supplied to the line. Sometimes, by delicate adjustments of the carbide feed mechanisms, the generators can be made to operate cooperatively for a period of time, but they soon lose the original adjustment and necessitate constant recalibration. Pressure regulators are sometimes used at the discharge ends of the generators so that they will all deliver gas at the same pressure to the common discharge line, but this is not wholly satisfactory and only adds to the complexity and cost of the generator equipment.

One object of this invention is to provide an improved carbide feed system for a bank of acetylene generators connected to a common discharge line which will function to cause all the generators to deliver acetylene to the discharge line at substantially the same pressure.

This is accomplished by using on each generator of the bank carbide feed mechanism having a movable element such as a plate or disc that controls the delivery of carbide from a hopper into the water in the generator, and controlling the movement of such element by a diaphragm or other pressure-responsive device exposed at one side to the pressure of the acetylene in the generator and loaded at the other side by a gas that is independent of the generated acetylene gas and its pressure and that is delivered to the diaphragm loading chambers of the carbide feed mechanisms of all of the generators at substantially the same pressure. Preferably the diaphragms of the carbide feed mechanisms of all of the generators are loaded by gas under a predetermined pressure from a single source.

Part of the system can be used to improve the operation of the carbide feed mechanism of a single acetylene generator when the feed mechanism is of the type in which a gas loaded diaphragm controls movement of a plate or disc or other element that in turn controls delivery of carbide to the water in the generator, and therefore a further object of the invention is to provide an improved carbide feed mechanism for a single generator.

The invention is illustrated in the accompanying drawing, in which:

Figure 1 is a vertical section through the hopper and carbide feed mechanism of an acetylene generator embodying the invention, a few of the parts being shown in side elevation;

2

Fig. 2 is a development of a portion of the valve lip constituting part of the carbide feed mechanism of Fig. 1; and

Fig. 3 is a schematic illustration of a carbide feed system for a bank of acetylene generators embodying the invention, each generator having a feed mechanism of the kind shown in Fig. 1.

Referring first to Fig. 1, the carbide hopper of a carbide to water type acetylene generator G is shown at 10. The carbide is usually in the form of small particles, as is well understood in the art. The hopper has a downwardly sloping bottom 11 at the center of which is a discharge opening 12. Carbide in the hopper is free to move downwardly through the opening 12 into a spout 13 from which it passes through an opening 14 onto a feed plate or disc 15 having a conical upper surface. A ring 16, projecting downwardly from the spout 13 and encircling its discharge opening 14, supports a flexible valve lip 17 which, when the feed plate 15 is in its raised non-feeding position, bears against the upper conical surface of the feed plate. The valve lip 17 may comprise a thin metal strip of the kind illustrated in Fig. 2, having a serrated lower edge that forms a continuous series of flexible fingers 18, and bent to circular or ring shape. When the feed plate 15 is drawn upward the fingers 18 of the valve lip prevent discharge of carbide particles around the edge of the feed plate. The flexible lower edge of the valve lip formed by the fingers 18 prevent the smaller size carbide particles from sifting past the larger ones in case large particles become lodged between the feed plate and the valve lip. An apron 19 acts as a shield to prevent condensate on the upper surfaces of the generating chamber 20 from dripping onto the feed plate or the surfaces surrounding the discharge opening 14.

40 The feed plate 15 is secured to the lower end of a stem 21 that is movable longitudinally within the spout 13. A flexible diaphragm 22 is clamped at its peripheral portion to the lower edge of a shell 23 by a clamping ring 24. The center portion of the diaphragm is clamped between upper and lower plates 25, 26, on the lower end of a stem 27 which projects upwardly within the shell 23. The upper end of the stem 27 slides in a bushing 27' that centers the stem and restrains 50 the diaphragm from buckling. The lower end of the stem 27 is secured to a hook 28 which is linked with an eye 29 secured to the upper end of the feed plate stem 21. Thus upward and downward movement of the diaphragm 22 raises 55 and lowers the feed plate 15.

A series of short pipes 30 extending through the sloping bottom 11 of the carbide hopper place the acetylene chamber 20 of the generator in communication with the space under the dia- 60 phragm 22, and therefore the underside of the

3

diaphragm is exposed to the pressure of the acetylene generated in the generator. A plate 31 in the shape of a truncated hollow cone having an opening 32 at its upper end prevents carbide particles from accumulating around the upper ends of the pipes 30 and keeps a space under the diaphragm clear of carbide particles so that the generated acetylene which passes from the upper ends of the pipes 30 and through the opening 32 in the plate has access to the under side of the diaphragm. The pipes 30 give the acetylene generated in the chamber 20 access to the space under the diaphragm without the necessity of the acetylene passing upward through the feed spout 16 and the carbide below the level of the hopper plate 11. In the event of a sudden pressure rise causing generated acetylene to pass into the hopper, as in the case of a rupture of the diaphragm 22, the acetylene will not pass through the carbide and the danger of moisture in the gas forming hot spots in the carbide will be averted.

The shell 23 and the diaphragm 22 form a gas-tight loading chamber 33 above the diaphragm. A diaphragm loading gas from an independent gas source is supplied to this chamber under predetermined constant pressure through a loading gas supply pipe 34 as hereinafter more fully described. When the generator is operating, the pressure of the gas in the loading chamber 33 above the diaphragm depresses the diaphragm and lowers the feed plate 15 to feed carbide into the body of water in the lower portion of the generator until the pressure of the generated acetylene acting on the under side of the diaphragm becomes high enough to move the diaphragm upward, thereby lifting the feed plate 15 to arrest the feeding of carbide.

The feed plate 15 may be held raised in its non-feeding position by means of a cam 35 which acts against the lower face of a flange 36 on the stem 21. The cam is secured to the inner end of a shaft 37 which is journaled to rotate in a pipe 38 in a gas-tight manner and which extends to a point outside of the hopper where it is connected to a handle 39. By partially rotating the handle 39 the cam may be turned either to its operative position shown in Fig. 1 in which it holds the feed plate 15 in its raised non-feeding position or to an inoperative position in which it permits the feed plate to move downward to feeding position.

A coil spring 40 located within a retainer 41 supported within the shell 23 reacts at its lower end against the retainer and at its upper end against a plate 42 secured to the stem 21. This spring counteracts some of the weight of the movable parts of the feed mechanism including the stem 21, the diaphragm 22, the stem 21, and the feed plate 15. If desired this spring may be made sufficiently strong so that it necessitates the presence of a higher gas pressure in the shell 23 than exists in the hopper 10. If a rupture of the diaphragm occurs, the generated acetylene would not then flow into the shell 23 and backward through the loading gas supply system where it may affect the operation of other generators connected in parallel in the manner hereinafter described.

When the generator is first placed in operation and no acetylene pressure exists, the handle 39 is rotated to turn the cam 35 to its inoperative position whereupon the diaphragm 22 and the feed plate 15 are lowered by the weight of the carbide supported on the feed plate. However, this re-

4

sults in the feeding of only a limited amount of carbide into the water in the generator. The truncated cone 31 restrains the movement of the carbide in the hopper and permits it to move only in a thin layer along the sloping bottom wall of the hopper toward the discharge opening 12. The spaces within the spout 13 and within the ring 16 become partially filled with carbide when the hopper is charged. A flexible disc 43, secured to the stem 21, closes the discharge opening 12 in the hopper bottom when the feed plate 15 is moved to its lowermost position and prevents further movement of carbide particles into the spout 13. Therefore only the carbide below the hopper opening 12 is discharged by the feed plate when the feed plate is completely open. For an additional discharge, feed plate 15 must be raised by rotating the handle 39 to permit the spout 13 and the space within the ring 16 to be recharged with carbide. Thus only measured amounts of carbide can be fed to the water within the generator when the feed plate is operated manually by the handle 39. The disc 43 also interrupts the feeding of carbide when the acetylene pressure becomes excessively low during normal operation of the generator.

The hopper is charged with carbide through an opening provided at the top of the hopper which is sealed by a cover plate 44 removably held in place by a yoke 45 and a clamping screw 46.

When the hopper is refilled with a new supply of carbide it is usually desirable to operate the feed mechanism manually by means of the handle 39 because the pressure of the acetylene in the generator is reduced substantially to atmospheric pressure before the hopper is refilled and must be built up to operating pressure before the feed mechanism will operate automatically in its intended way. Moreover, a large quantity of the acetylene gas first generated is absorbed by the water in the generator until the water becomes saturated, especially when the water has been changed as is usually done when the hopper is recharged with carbide. Heretofore, to offset this and to rapidly raise the generator pressure, it has been customary to manually precipitate a supply of carbide into the water in the generator until the pressure of the generated gas closes the feed plate. However, with this practice a considerable excess of carbide is usually precipitated before the feed plate can be closed with the result that an undesirable pressure rise, or after-generation, occurs. The present feed mechanism avoids this since only a measured amount of carbide can be discharged during the full opening of the feed plate 15, as above described. During regular operation of the generator, however, when the generator is supplying a constant flow of acetylene, the diaphragm 22 will move up and down almost continuously, thereby maintaining practically a continuous sifting of carbide from the feed plate at the rate required to maintain the desired acetylene pressure within the generator. One advantage of this type of feed mechanism is that the response of the diaphragm is extremely rapid, closing the feed plate quickly to avoid over-generation, and opening it without a lag to precipitate more carbide. Consequently the generator pressure never varies more than a small amount from the desired pressure and a very uniform pressure may be maintained.

The above-mentioned loading gas supply pipe 34 for supplying an independent gas to the loading chamber 33 above the diaphragm is connected with a source of gas, other than the acetylene gen-

erated in the generator, in the manner shown in Fig. 3. The gas source may comprise a cylinder C containing some compressed gas such as nitrogen which is delivered to a feed line 47 through an adjustable pressure regulator R that maintains the gas pressure in the feed line at the desired level. Any gas can be used but it is preferable to use an inert gas to avoid the danger which might result if leakages occur at the shell 23. From the feed line 47 a branch pipe 48 delivers the gas through a shut-off valve 49 to the above-mentioned loading gas supply pipe 34 leading to the shell 23 within the carbide hopper of the acetylene generator G. As already made clear, when the cam 35 (Fig. 1) is in its inoperative position, the gas admitted to the chamber 33 above the diaphragm exerts a downward force against the diaphragm and moves it downward when the pressure of the generated acetylene in the generator is not sufficient to balance the downward force. The feed plate is thereby lowered and a quantity of carbide is permitted to drop into the water in the generator until the additional acetylene generated increases the pressure at the under side of the diaphragm sufficiently to move it upward and lift the feed plate to its closed position.

The invention makes it possible to provide a carbide feed system for a bank of acetylene generators in which the individual carbide feed mechanisms on the generators will all operate in unison. Fig. 3 shows not only the acetylene generator G above referred to but two additional generators G₁ and G₂. These are all connected to a common acetylene discharge line 50. The loading gas supply pipes 34₁ and 34₂ that supply the loading gas for the diaphragms of the feed mechanisms of the generators G₁ and G₂ are connected to the gas feed line 47 in the same manner that the loading gas supply pipe 34 of the generator G is connected to it, namely, by means of branch pipes 48₁ and 48₂, respectively, and shut-off valves 49₁ and 49₂, respectively. Any desired number of generators may be included in the bank with the loading chambers of the diaphragms of their carbide feed mechanisms all connected to the gas feed line 47 as above described. Any generator may be excluded from the bank without affecting the others by closing the corresponding shut-off valve 49.

A reservoir 51 is preferably connected in the gas feed line 47 in advance of the first acetylene generator, and a vent 52 is preferably provided just beyond the pressure regulator R. Large displacements of the carbide feed diaphragms might cause some compression of the gas in the gas line if the volume of the system is sufficiently small. This would result in a slight increase of pressure on the upper side of the diaphragms that might interfere with precise regulation, although the effect, for all practical purposes, would probably be negligible. The volume of the reservoir 51 is such that no harmful compression of the gas can occur in the loading gas line when large displacements of the carbide feed diaphragms take place. A small continuous discharge of gas takes place at the vent 52 that permits the pressure regulator R to function properly and maintain a constant pressure in the gas feed line 47. The discharge of gas from the vent 52 also permits the setting of the pressure regulator R to be lowered when so desired. The system is operative without the reservoir 51 and the vent 52 but their use is advisable as a precautionary measure to ensure satisfactory operation of the system under all conditions.

A relief valve 53 is set to open at the maximum tolerable pressure in the gas line 47 so that the gas line is vented in case leakage at the pressure regulator R causes the pressure in the gas line to rise.

It will now be seen that since the diaphragms of the individual carbide feed mechanisms of the generators are not spring-loaded but are loaded by gas from a single source that passes through the pressure regulator R, the pressure created by the loading gas on the carbide feed diaphragms of all of the generators is uniform throughout the bank of generators, thereby causing all of the feed mechanisms to behave identically. The pressure of the gas produced in each of the generators will therefore be the same and will be determined by the adjustment of the pressure regulator R and all of the generators will share equally in supplying the total flow of generated acetylene.

While the invention has been described in connection with acetylene generators that have carbide feed mechanism of the type in which a feed plate is moved vertically by a diaphragm, it is also applicable to generators that have carbide feed mechanism of the type in which a motor, such as a weight motor, rotates a carbide feed element such as a plate or disc and the rotation of the element is controlled by a friction brake which in turn is controlled by a regulator having a diaphragm which is exposed at one side to the pressure of the generated acetylene and which is spring-loaded at its other side. An acetylene generator having carbide feed mechanism of this type is disclosed in the patent to George M. Deming No. 2,085,084 issued June 29, 1937. In applying the invention to carbide feed mechanism of the kind shown in the Deming patent the loading spring for the diaphragm of the regulator would, of course, be dispensed with and the diaphragm would be gas loaded in the manner hereinbefore described. With the carbide feed mechanism revised in this way a number of the generators could be connected to a common acetylene discharge line and a carbide feed system employed for them of the kind above described and illustrated in Fig. 3.

Reference is made to my copending application Ser. No. 34,916, filed June 24, 1948, disclosing a further modification of the invention claimed herein.

I claim:

1. In a carbide to water acetylene generator, carbide feed mechanism comprising a carbide hopper, a movable element controlling the delivery of carbide from the hopper to the water in the generator, a diaphragm, means whereby the diaphragm controls the movement of said movable element, said diaphragm being exposed at one side to the pressure of the acetylene produced in the generator, a gas loading chamber at the other side of the diaphragm, a source of compressed gas that is independent of the acetylene produced in the generator, and means for delivering such gas at a substantially constant predetermined pressure to said loading chamber.

2. In a carbide to water acetylene generator, carbide feed mechanism comprising a carbide hopper, a movable element controlling the delivery of carbide from the hopper to the water in the generator, a diaphragm, means whereby the diaphragm controls the movement of said movable element, said diaphragm being exposed at one side to the pressure of the acetylene produced in the generator, a gas loading chamber at the other side of the diaphragm, a source of compressed gas

that is independent of the acetylene produced in the generator, a gas feed line leading from said source of compressed gas to said loading chamber, and an adjustable gas pressure regulator in said line.

3. In a carbide to water acetylene generator, carbide feed mechanism comprising a carbide hopper, a movable element controlling the delivery of carbide from the hopper to the water in the generator, a diaphragm, means whereby the diaphragm controls the movement of said movable element, said diaphragm being exposed at one side to the pressure of the acetylene produced in the generator, a gas loading chamber at the other side of the diaphragm, a source of compressed gas that is independent of the acetylene produced in the generator, a gas feed line leading from said source of compressed gas to said loading chamber, a gas reservoir in said line, and an adjustable gas pressure regulator in said line in advance of said reservoir.

4. In a carbide to water acetylene generator, carbide feed mechanism comprising a carbide hopper, a movable element controlling the delivery of carbide from the hopper to the water in the generator, a diaphragm, means whereby the diaphragm controls the movement of said movable element, said diaphragm being exposed at one side to the pressure of the acetylene produced in the generator, a gas loading chamber at the other side of the diaphragm, a source of compressed gas that is independent of the acetylene produced in the generator, a gas feed line leading from said source of compressed gas to said loading chamber, a gas reservoir in said line, an adjustable gas pressure regulator in said line in advance of said reservoir, and a gas vent in said line between the pressure regulator and the reservoir.

5. In a carbide to water acetylene generator, carbide feed mechanism comprising a carbide hopper, a movable element controlling the delivery of carbide from the hopper to the water in the generator, a diaphragm, means whereby the diaphragm controls the movement of said movable element, said diaphragm being exposed at one side to the pressure of the acetylene produced in the generator, a gas loading chamber at the other side of the diaphragm, a source of compressed gas that is independent of the acetylene produced in the generator, a gas feed line leading from said source of compressed gas to said loading chamber, an adjustable gas pressure regulator in said line, and a relief valve in said line.

6. In a bank of carbide to water acetylene generators all connected to a common acetylene discharge line, a carbide feed system for the generators comprising a carbide hopper on each generator, a movable element associated with each of the hoppers controlling the delivery of carbide from the hopper to the water in the corresponding generator, a controlling diaphragm for each of said elements, means whereby each diaphragm controls the movement of the corresponding movable element, each of the diaphragms being exposed at one side to the pressure of the acetylene produced in the corresponding generator and having a gas loading chamber at its other side, a source of compressed gas that is independent of the acetylene produced in the generators, and means for delivering such gas at a substantially constant predetermined pressure to the loading chambers of the diaphragms associated with all of the generators.

7. In a bank of carbide to water acetylene generators all connected to a common acetylene dis-

charge line, a carbide feed system for the generators comprising a carbide hopper on each generator, a movable element associated with each of the hoppers controlling the delivery of carbide from the hopper to the water in the corresponding generator, a controlling diaphragm for each of said elements, means whereby each diaphragm controls the movement of the corresponding movable element, each of the diaphragms being exposed at one side to the pressure of the acetylene produced in the corresponding generator and having a gas loading chamber at its other side, a single source of compressed gas that is independent of the acetylene produced in the generators, and means for delivering such gas to the loading chambers of the diaphragms of all of the generators.

8. In a bank of carbide to water acetylene generators all connected to a common acetylene discharge line, a carbide feed system for the generators comprising a carbide hopper on each generator, a movable element associated with each of the hoppers controlling the delivery of carbide from the hopper to the water in the corresponding generator, a controlling diaphragm for each of said elements, means whereby each diaphragm controls the movement of the corresponding movable element, each of the diaphragms being exposed at one side to the pressure of the acetylene produced in the corresponding generator and having a gas loading chamber at its other side, a source of compressed gas that is independent of the acetylene produced in the generators, a gas feed line leading from said source of compressed gas to the loading chambers of the diaphragms of all of the generators, and an adjustable gas pressure regulator in said line.

9. In a bank of carbide to water acetylene generators all connected to a common acetylene discharge line, a carbide feed system for the generators comprising a carbide hopper on each generator, a movable element associated with each of the hoppers controlling the delivery of carbide from the hopper to the water in the corresponding generator, a controlling diaphragm for each of said elements, means whereby each diaphragm controls the movement of the corresponding movable element, each of the diaphragms being exposed at one side to the pressure of the acetylene produced in the corresponding generator and having a gas loading chamber at its other side, a source of compressed gas that is independent of the acetylene produced in the generators, a gas feed line leading from said source of compressed gas to the loading chambers of the diaphragms of all of the generators, and an adjustable gas pressure regulator in said line.

10. In a bank of carbide to water acetylene generators all connected to a common acetylene discharge line, a carbide feed system for the generators comprising a carbide hopper on each generator, a movable element associated with each of the hoppers controlling the delivery of carbide from the hopper to the water in the corresponding generator, a controlling diaphragm for each of said elements, means whereby each diaphragm controls the movement of the corresponding movable element, each of the diaphragms being exposed at one side to the pressure of the acetylene produced in the corresponding generator and having a gas loading chamber at its other side, a source of compressed gas that is independent of the acetylene produced in the generators, a gas feed line leading from said source of compressed

gas to the loading chambers of the diaphragms of all of the generators, a gas reservoir in said line, an adjustable gas pressure regulator in said line in advance of said reservoir, and a gas vent in said line between the pressure regulator and the reservoir.

11. In a bank of carbide to water acetylene generators all connected to a common acetylene discharge line, a carbide feed system for the generators comprising a carbide hopper on each generator, a movable element associated with each of the hoppers controlling the delivery of carbide from the hopper to the water in the corresponding generator, a controlling diaphragm for each of said elements, means whereby each diaphragm 15

5 controls the movement of the corresponding movable element, each of the diaphragms being exposed at one side to the pressure of the acetylene produced in the corresponding generator and having a gas loading chamber at its other side, a source of compressed gas that is independent of the acetylene produced in the generators, a gas feed line leading from said source of compressed gas to the loading chambers of the diaphragm of 10 all of the generators, an adjustable gas pressure regulator in said line, and a relief valve in said line.

HARRY HOOPER.
